UNITED STATES PATENT OFFICE.

ARTHUR L. STANFORD, OF WAUKEGAN, ILLINOIS.

DRILLING-MACHINE.

SPECIFICATION forming part of Letters Patent No. 371,859, dated October 18, 1887.

Original application filed May 5, 1887, Serial No. 237,274. Divided and this application filed August 18, 1887. Serial No. 247,239.
(No model.)

To all whom it may concern:

Be it known that I, ARTHUR L. STANFORD, a citizen of the United States, residing at Waukegan, in the county of Lake and State of Illinois, have invented a new and useful Improvement in Hand Metal-Drills, (for which I made application for Letters Patent May 5, 1887, Serial No. 237,274,) of which the following is a divisional specification.

10 The object of my invention is to improve the construction of hand-drills for boring metal; and the invention, which is an improvement on the one described in my patent of March 1, 1887, No. 358,755, consists in the 15 features and combinations hereinafter described and claimed.

In the accompanying drawings, Figure 1 is a side elevation of my improved hand metal-drill; Fig. 2, a vertical sectional view of the 20 same, and Fig. 3 a plan sectional view taken in the line xx of Fig. 2.

A is the pivot-piece to come in contact with the frame opposite the metal to be drilled; B, the cover for the inner end of the pivot-piece; 25 C, the feed-screw; D, the lever for turning the feed-screw; E, the ratchet-wheel engaging with the lever D, for operating the hand-feed or for reversing the feed-screw, and which is also provided with a clutch to hold the pinion F rigid with the feed-screw; F, a pinion which 30 is loose on the feed-screw, except when the automatic feed is used; G, the internal gear-wheel to aid in regulating the relative movement of the feed-screw and feed-cylinder; H, the inner feed-cylinder, and h a pinion on the 35 end thereof; I, the outer feed-cylinder; J, the drill-bit carrier; K, a piece encircling a portion of the drill-bit carrier, and which also aids in forming the clutch, and k a projecting 40 portion thereof; L, rollers; M, the drill-bit; N, an eccentric disk furnishing a bearing for the internal gear-wheel, and O a key to prevent the outer cylinder turning on the drill-bit carrier.

45 My improved hand metal-drill may be used in any convenient form of frame—as, for instance, the one shown in my patent of March 1, 1887, above referred to.

The pivot-piece at the side of the frame opposite the metal to be drilled is provided with a spherical bearing, and is so constructed as

to form suitable bearings and protection for the parts which comprise the automatic feed. Its spherical bearing comes in contact with the side of the frame, and, being spherical, permits a reasonable adjustment of the drill-bit, and thus obviates the necessity of having it set exactly at right angles to the metal to be drilled. At the opposite side of the end piece or metal on which this spherical bearing is formed is the bearing for the end of the feed-screw. The box or housing of the pivot-piece furnishes protection to the working parts against sand, dirt, &c., and its inner end or cover a bearing for the inner cylinder. 65

The ratchet-wheel E, which is stationary in the hand-feed, is movable longitudinally when desired to be used in the automatic feed, and it is provided with a clutch at its inner side, which permits it to engage with the loose pinion F of the automatic feed devices. These automatic feed devices are so constructed as to give an unequal number of revolutions to the outer feed-cylinder and feed-screw, as follows: The pinion F is made rigid with the 70 feed-screw by having the clutch of the ratchet-wheel engaged therewith, as already described. The pinion h , which is integral with the inside cylinder, is so constructed that it can have no rotary movement relative to the feed-cylinder. 75 These two pinions preferably have an unequal number of cogs, which are adapted to engage with an internal gear-wheel, G, which gear-wheel preferably has an equal number of cogs in both its parts. This construction can 80 be reversed, so as to have an unequal number of cogs in each part of the internal gear-wheel and an equal number in the other two pinions; or all the pinions may be provided with an unequal number of cogs, but of course in 85 such a way as not to interfere with their movements or operations, the only object in this respect being to give an unequal number of revolutions to the outer feed-cylinder and feed-screw. This internal gear-wheel, G, is preferably of peculiar construction, having its 90 central portion plane to bear on the eccentric disk N, through which the feed-screw passes, and its adjacent side portions provided with cogs to mesh into the pinions F and h . This 95 eccentric disk is made rigid with the pivot-piece by means of a projecting portion or stud

engaging with the pivot-piece or its cover. The hole for the feed-screw in this eccentric disk is of course at a suitable distance from its center to cause the internal gear-wheel to thus engage with these pinions, the object of this construction being to give an unequal number of revolutions to the feed-screw and feed-cylinder.

It will of course be understood that the feed-screw and feed-cylinder are so threaded as to permit of their proper relative movements to make the feed effective.

As already stated, the inside cylinder terminates in a pinion, and it extends within the feed-cylinder to the head of the feed-screw. It is also provided with a longitudinal slot, into which a screw, stud, or other suitable device is inserted to cause it to revolve with the feed-cylinder. The outer cylinder is made large enough to receive the inner cylinder, and is screwed onto the drill-bit carrier and made rigid by a key, O, passing through it and such carrier. I prefer to use a split key for this purpose, inasmuch as it may be readily inserted or removed. The diameter of the drill-bit carrier is sufficient to receive the drill-bit and permit the latter to be shoved into it to the point of its seat.

Encircling a portion of the drill-bit carrier is a peculiarly-formed piece, K, preferably of oblong shape, the inner surfaces of which are adapted to come in contact with rollers, and also to form recesses for springs. The bearings for these rollers and springs should of course be in position and otherwise be adapted to permit their operation, as hereinafter described.

The rollers, which are equal in length to the thickness of the encircling-piece K, are intended to be used in pairs, so as to bind the drill-carrier at opposite lines or points. When in proper position, or in what I consider to be the best position for this purpose, a line drawn through the diametrical center of the rollers will also pass through the diametrical center of the drill-carrier. These rollers, being placed at opposite sides of the drill-carrier, of course prevent any unequal rubbing or binding. Within the recesses formed in the inner surface of the encircling piece are placed two small flat or leaf springs the curvature

of which is so slight as to permit their being straightened out by pressure or otherwise without breaking or losing their resiliency. This enables them to withstand the pressure of the rollers, and thus obviates the necessity of frequently replacing the springs. The recesses in which these springs are placed are so close to the rollers as to prevent their falling out or becoming displaced; or, in other words, these recesses are such distance from the lines on the curved surfaces of the encircling part where the rollers bind as to only leave space enough for the springs.

I claim—

1. In a hand-drill, an automatic feed comprising an outer feed-cylinder, an inner cylinder provided with a pinion revolving equally with the outer cylinder, a feed-screw provided with a pinion rigid therewith when the automatic feed is used, and an internal gear-wheel provided with bearings and engaging with said two pinions, substantially as described.

2. In a hand-drill, a feed-screw having a ratchet clutch-wheel mounted thereon, and an automatic feed having a pinion engaging with said ratchet clutch-wheel, substantially as described.

3. In a hand-drill, an internal gear-wheel having one portion of its inner circumference plane and another portion provided with cogs, substantially as described.

4. In an automatic feed for a hand-drill, an internal gear-wheel having the central portion of its inner circumference plane and the adjacent portions of its inner circumference provided with cogs, substantially as described.

5. In an automatic feed for a hand-drill, an eccentric disk mounted on the feed-screw and made rigid with the pivot-piece, substantially as described.

6. In an automatic feed for a hand-drill, an internal gear-wheel and an eccentric disk mounted on the feed-screw and made rigid with the pivot-piece, and forming a bearing for the gear-wheel, whereby the gear-wheel is held in position and made to engage with its pinions, substantially as described.

ARTHUR L. STANFORD.
